UNITED STATES PATENT OFFICE.

OTTO INTZE, OF AACHEN, PRUSSIA, GERMANY.

GASOMETER.

SPECIFICATION forming part of Letters Patent No. 348,913, dated September 7, 1886.

Application filed June 13, 1885. Serial No. 168,614. (No model.) Patented in Germany March 31, 1883, No. 24,951, and in Belgium May 18, 1885, No. 68,901.

To all whom it may concern:

Be it known that I, OTTO INTZE, a subject of the King of Prussia, residing at Aachen, Prussia, German Empire, have invented certain new and useful Improvements in Gasometers, (for which I have obtained Letters Patent in the following countries, dated and numbered as follows: Belgium, May 18, 1885, No. 68,901^b; Germany, March 31, 1883, No. 24,951;) and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Referring to the drawings, Figures 1 and 2 are vertical axial sections of a gas-holder, the tank of which is provided with a bottom embodying my improvements.

In gas-holders sheet metal is now preferably employed in place of masonry in the construction of the tanks. Up to the present time these tanks have been constructed with a flat bottom seated on a level surface of the ground or upon solid masonry or concrete. This construction, however, renders it very difficult in case of leakage to locate the defective part or to gain access to the defective part, nor is it possible to protect the bottom against corrosion by protective agents after the holder is placed in position.

This invention has for its object certain improvements in fluid-reservoirs of great capacity—such, for instance, as the water-tanks for gas-holders—the said improvements being applicable to all other classes of fluid-reservoirs or storage-tanks.

This invention is designed as an improvement in the construction of the bottom of the reservoirs or tanks referred to and described in my application for Letters Patent of even date with this, Serial No. 168,613; and it consists in constructing the bottom of the tank or reservoir of a counter-bottom, which may be conical or concave or convex or hemispherical, and a bottom formed by re-entering and salient angles, whose apices lie in vertical planes parallel with the vertical axis of the tank or reservoir, one or more of said salient

angles forming a seat or seats for the support of said tank or reservoir, and in combination therewith of one or more supports or seat-rings, substantially as hereinafter fully described.

In the drawings, H indicates the tank of the gas-holder, whose bottom B is formed by two reversely-inclined surfaces, b' b², that form a salient angle, b, at the line of junction of said bottom B and the counter-bottom C, and a re-entering angle, b³, at the line of junction of the reversely-inclined surfaces b' b², a second salient angle, b⁴, being formed at the point of junction between the inclined surface b² and a counter-bottom, C, such salient angle forming a seat, x, from which the tank is supported, either upon a suitable seat-ring, a, or directly from a foundation-wall or other suitable support, A, of such height as to afford ready and free access to the entire outer surface of the bottom of the tank H.

Instead of supporting the tank from a single seat, it may be supported from a plurality of seats, as shown in Fig. 2. In this construction the bottom B is supported from seat-rings a and a'. The inner ring serves as a bearing for the seat x, formed at the line of junction between the counter-bottom C and the reversely-inclined surface b', the re-entering angle being formed by said surface b² and the inclined surface b', the second salient angle, b, being here formed by said inclined surface b' and an inclined surface, b²x, that is connected with the reservoir, said second salient angle forming also a seat, x, for the support of the cylinder. In this case there is an outer conical bottom, B, an intermediate angular bottom, B', and counter-bottom C. It will be observed that the apices of the salient and re-entering angles all lie in vertical planes parallel with the axis of the tank, so that the forces exerted upon the supports for said tank are exerted in a vertical direction, there being no lateral pressures. I am therefore enabled to use supports of considerably less strength than usual, and combine several independent supports, if desired, and yet afford free access to the entire outer surface of the bottom of the tank.

The counter-bottom C may have any desired form, provided it be such that the pressures exerted will be in a vertical direction. Thus the bottom may be conical, convex, hemi-

spherical, or concave. A further advantage obtained in this construction of bottom is that a very material saving in labor is effected in preparing the ground for the reception of the foundations for both the tank and the supports for the bell, as referred to in the application hereinbefore mentioned.

5 *e* is the gas-induction pipe, and *D* the gas-bell or inverted cylinder, supported as usual 10 from standards by means of chains provided with counter-weights in the well-known manner.

Having thus particularly described my said invention, what I claim, and desire to secure 15 by Letters Patent, is—

1. A metallic reservoir for fluids having its inclosing-wall and bottom connected and constructed to form salient and re-entering angles, one or more of said salient angles constituting the seat or seats for said reservoir, in combination with a bearing for said seat or seats, substantially as and for the purpose specified.

2. A metallic water-tank for gas-holders

having the inclosing-wall and bottom connected and constructed to form salient and re-entering angles, said salient angles constituting the bearings or seats for the reservoir, in combination with independent foundation walls or supports upon which the angular bearings of the reservoir are seated, substantially as and for the purpose specified.

3. In fluid-reservoirs, the combination of the inner hemispherical or convex bottom, *C*, and the outer conical bottom, *B*, with the intermediate conical bottom, *B'*, as and for the purpose set forth.

4. In fluid-reservoirs, the combination of the hemispherical or convex counter-bottom *C*, the conical bottom *B*, and the intermediate conical or angular bottom, *B'*, with the seat-rings *a* and *a'*, as and for the purpose specified.

In testimony whereof I affix my signature in presence of two witnesses.

OTTO INTZE.
